UNITED STATES PATENT OFFICE.

ARTHUR J. BOYNTON, OF WILMETTE, ILLINOIS, ASSIGNOR, BY MESNE ASSIGNMENTS,
TO VICTOR CHEMICAL WORKS, OF CHICAGO, ILLINOIS, A CORPORATION OF ILLINOIS.

COMBUSTION SYSTEM.

Application filed October 16, 1924. Serial No. 743,869.

This invention has to do with improvements in combustion systems. The invention has to do with the burning of gases and fumes where the purpose of the combustion 5 is not merely the utilization of the heat contained in the gases of combustion, but also the combustion of elemental substances resident in or carried by the gas, where the primary purpose is the use of the products 10 of combustion for other purposes than the utilization of their heat of combustion and sensible heat. For example, the system of the present invention is intended for the production of oxides from elemental substances 15 either gaseous or solid or in the form of fumes, the solids and fumes being resident in and carried by the gases. The system of the present invention also is for the production of higher oxides from substances 20 ready partially oxidized where the process of the combustion is to use the oxidized substances for other reasons than that of their sensible heat and the heat of combustion.

The combustion as practiced according to 25 the present system necessarily also results in the generation of heat, but this heat generation is largely an incident to the fundamental purpose of the invention which is the control of the combustion in such a 30 way as to give the desired end products which it is sought to produce.

The application of this system of combustion will be better understood by way of illustration or example; but in giving the 35 same, I wish it clearly understood that such example is purely illustrative and is not intended as a limitation on the process or practice of the invention, except as provided in the claims.

As illustrative, reference may be had to the 40 production of phosphoric acid, P_2O_5 , by the operation of a vertical shaft furnace in conjunction with a series of hot stoves. In such case, the phosphate rock together with the necessary amount of coke and suitable fluxing 45 agents is introduced into the upper end of a vertical shaft furnace, such, for example, as a small blast furnace. The operation in this furnace is so regulated that the gases taken off at the top include carbon monoxide and fumes including phosphorus fumes. These 50 products are then carried to the hot stoves used for preheating the air blast of the shaft furnace. The gases and fumes are burned in the hot stoves on alternate periods of com-

bustion, and air, so as to preheat the air blast in the well understood manner. The burned products of combustion from the hot stoves may then be taken through a suitable cooler and finally delivered to a 60 precipitation apparatus wherein the P_2O_5 is recovered.

The successful practice of this process, however, requires that the combustion in the 65 hot stoves shall be practically perfect, substantially without excess of oxygen. At the same time a sufficient amount of oxygen for complete combustion must be supplied so as to insure the proper conversion of the phosphorus bearing fumes.

In the above process a practically perfect 70 control of the oxygen requirements at the hot stoves, and the consequent ability to produce the desired end product, is the fundamental and controlling feature, and the actual 75 production of heat in the hot stoves is incidental to this fundamental object. In fact, if more convenient or desirable, the combustion could be practiced in apparatus other than hot stoves, the air blast in such case 80 being preheated in some other way, if pre-heating should be a desirable or necessary requirement.

The perfect combustion of the gases and fumes in the hot stoves depends largely upon 85 their composition. The combustion must be carried forward with the total oxygen requirements of the carbon monoxide and phosphorus in view, and not simply in such a manner so as to satisfy the combustion 90 requirements of the carbon monoxide gas.

The supply of gas and fumes will necessarily fluctuate from time to time and the 95 oxygen requirements should be immediately varied in accordance therewith. In order to insure complete combustion substantially without excess of oxygen at all times, the air supply to the hot stoves should be so controlled from instant to instant as to maintain the proper ratio of air to gas and fumes 100 at all times. The perfect combustion can be ensured by so controlling the supply of air as compared to gas and fumes that there is maintained a definite relation between static pressures of the combustible gas and 105 fume and of the air and corresponding definite proportions between the areas of exit from the burner of the gas and fume and of the air. Certain regulators have heretofore been devised for instantaneously so 110

controlling the air supply as to maintain this ratio, including the type of device shown in Letters Patent to Stamps No. 1,378,429, of May 17, 1921, and Letters Patent to Steinbart No. 1,306,446 issued June 10, 1919. The types of devices disclosed in these patents are illustrative of devices capable of giving the accurate instantaneous control and regulation of air supply, and are mentioned by way of illustration only, except as I may limit myself in the claims.

In the drawings:

Figure 1 shows diagrammatically one layout of apparatus for practicing the present invention; and

Fig. 2 shows in fragmentary vertical section a type of burner construction of the general type of the aforesaid Steinbart patent.

In the layout illustrated in the drawings, the initial stages of the process are practiced in a vertical shaft furnace 3 which is illustrated as being of the type of a small blast furnace. It includes the hearth section 4, bustle pipe 5, tuyères 6, bosh 7, throat section 8, cinder notch 9, charging head 10 and downcomer 11 of the usual form of the blast furnace. Ordinarily, however, the blast furnace used in the present invention, when a blast furnace is used, will be relatively small and have a height of probably not to exceed twenty-five feet. The hot stoves are designated by the numerals 12, 13 and 14 respectively. The air blast for the bustle 5 is delivered through a pipe 16 which connects to the various hot stoves by the connections 17 under control of dampers. These hot stoves may be of any suitable type, such as the familiar Cowper type.

The air blast delivered to the hot stoves is supplied by the main 18 through the connections 19 under control of suitable dampers.

The gases and fumes delivered from the blast furnace downcomer 11 are carried to the hot stoves by a flue 20. In some cases, the dust catcher 21 may be placed between the downcomer 11 and flue 20 so as to remove certain materials, but the fumes should not be removed, since these are one of the primary objects of the operation conducted in the vertical shaft furnace. The flue 20 is connected to the different hot stoves by connections 22 under control of the proper dampers. Air connections 23 serve for admission of the air for combustion to burn the gases and fumes supplied through the connections 22.

A products of combustion flue 24 is provided for removing the products of combustion from the different stoves by the connections 25 under control of suitable dampers in the manner well understood in the art.

When any given stove is being operated on gas, the gas is admitted through the connection 22, the proper air for combustion be-

ing supplied by the connection 23 thereto. The gas and fumes are oxidized and pass through the checker work of the stove to heat the same. The products of combustion are then delivered to the flue 24 and conducted to the subsequent apparatus. When any given stove is being operated on air, the same is admitted from the flue 18 to such stove and passes through the stove and is heated by the hot checker work thereof. This hot blast is then delivered through the hot blast main 16 to the bustle pipe. The above operations are well known and understood in the art.

In order to secure the necessary accuracy of control of combustion of gases and fumes delivered to each hot stove, there is provided a regulator, such, for example, as that illustrated in Fig. 2. The hot stove has the opening 26 provided with an end nipple 27. Back of this end nipple is a combustion nozzle 28 including a central gas opening 29 surrounded by an annular air passage 30. The areas of the opening 29 and air passage 30 are in definite ratio and do not vary. Air is delivered to this passage 30 from a box 31 which surrounds the throat 32 through which the gas and fume are delivered. As a result the combustion begins at the point where the gas and fumes come into contact with the surrounding layer of air.

The gas delivered through the throat 32 comes from a box 33 preferably provided with a transverse partition 34. This partition reaches the full height of the box 33, but does not reach the full width thereof, so that the gases and fumes are allowed to swirl around the side edges of the partition. The gases and fumes are delivered to this box 33 by a connection 35 which in turn connects to the pipe 20. In Fig. 1, which is more or less diagrammatic in form, the pipe 20 is shown as below the position of the connection into the hot stove, whereas in Fig. 2, which is a more correct illustration, the connection 35 is shown as reaching downwards towards the hot stove.

The air delivered by the box 31 comes in the first instance from a flue 36 and through a throat 37. A butterfly valve 38 is placed in the throat 37 and is controlled by a lever arm 39 at the outside of the throat. This lever arm in turn connects by a bell crank 40 and links 41 and 42 with a piston inside of a regulator 43. Pipes 43^a and 43^b connect the chambers 31 and 33 with the sides of the piston so that the valve 38 is operated according to the differential pressure. This regulator is of the general type of the aforesaid Steinbart patent, and is so constructed that the amount of opening of the butterfly valve is proportional to the relation of the static pressure of the combustible gas and fume in the box 33 as compared to the static pressure of the air in the box 31.

The perfectly oxidized materials coming from the pipe 24 are passed through a cooler 44 and thence by a connection 45 to a suitable precipitation apparatus designated generally by the numeral 46. This may be of any suitable form, such as an electric precipitation apparatus of the type of the Cottrell United States Patents Nos. 895,729, issued August 11, 1908; 945,917, issued January 11, 1910; 1,016,476, issued February 6, 1912; 1,035,422, issued August 13, 1912; and 1,067,974, issued July 22, 1913.

These electric precipitation devices include separated electrodes located in a passage 15 through which the material to be treated is passed, said electrodes being subjected to high potential electric currents, so that the gases flowing between them are subjected to a severe electro-static action. In case there 20 should be present unoxidized products in the gases flowing through these Cottrell devices, there would be serious danger of explosion due to ignition of some of the gases by electric sparks. This is an additional reason 25 why it is very desirable to be able to deliver the gases from the burners to the precipitation apparatus substantially without excess of oxygen and yet in fully oxidized condition.

30 In some cases the amount of gas and fumes delivered from the vertical shaft furnace will be greater than necessary to supply the heat needed for operation of the hot stoves to the degree necessary for the hot air blast. 35 When this is the case there will be a surplus of gas and fumes available for the heating of boilers or other devices. I have, therefore, illustrated in Fig. 1 a boiler diagrammatically by the numeral 47. The same is 40 fed with the surplus gas by a connection 48 from the flue 20; and the oxidized materials produced in the boiler furnace by combustion of the gas and fumes are then returned to the products of combustion flue 24 by a 45 connection 49. In the case of combustion of surplus materials, the same should also be perfectly oxidized if possible; and it is, therefore, contemplated that the combustion of such surplus gas and fumes shall also be 50 conducted under control of a regulator of the general type of the aforesaid Stamps and Steinbart patents.

It is also noted that inasmuch as the combustion of the gas and fumes is primarily for the purpose of generating certain desired end products, the same may be conducted either in conjunction with heat absorbing devices for the useful application of the heat generated by the combustion, or independently of such heat absorbing devices. For example, a burner of the general type of the aforesaid Stamps and Steinbart patents might be used to advantage for the combustion of the gas and fumes within a closed 55 chamber, in such a manner as to produce

practically perfect combustion, the products of combustion being afterwards carried to a suitable precipitation apparatus for recovery of the desired end products. It is also noted that with the burners, such as 70 shown in the aforesaid Steinbart patent, the proportions of combustible gas and fumes and of air are accurately controlled by establishing a definite relationship between the static pressures of the combustible gas and 75 fumes and of the air, and corresponding definite proportions between the areas of exit from the burner of the gas and fume and of the air.

While I have herein shown and described 80 only a single embodiment of the features of my present invention, still I do not intend to limit myself to the same, except as I may do so in the claims.

I claim:

1. Apparatus for the recovery of phosphoric acid or other oxides from raw materials comprising in combination a vertical shaft furnace having means for introduction of the raw materials and fuel and fluxing material at the top, together with a suitable gas and fumes top delivery connection and having suitable tuyères in its lower portion, of hot stoves in conjunction with said furnace, hot blast connections therefrom to the furnace tuyères, a connection for the delivery of gas and fumes from the furnace to the hot stoves for combustion therein of gas and fumes necessary to heat the air blast for the furnace, an auxiliary combustion chamber for surplus gas and fumes, a gas and fumes connection thereto, regulators at the hot stoves and at the auxiliary heat generator operable according to the differential of pressure between gas and fumes supply and air supply thereto for insuring substantially perfect combustion therein for the purposes specified, a cooler, products of combustion connections from the hot stoves and auxiliary heat generator to the cooler, Cottrell apparatus, and products of combustion and fumes connections from the cooler thereto, substantially as described.

2. Apparatus for the recovery of phosphoric acid or the like from raw materials comprising in combination a furnace having means for introduction of the raw materials and fuel and fluxing material, together with a suitable gas and fumes delivery connection and having suitable tuyères, of hot stoves in conjunction with said furnace, hot blast connections therefrom to the furnace tuyères, a connection for the delivery of gas and fumes from the furnace to the hot stoves for combustion therein of gas and fumes necessary to heat the air blast for the furnace, an auxiliary heat generator for surplus gas and fumes, a gas and fumes connection thereto, regulators at the hot stoves and at the auxiliary heat generator operable accord-

ing to the differential of pressure between gas and fumes supply and air supply thereto for insuring substantially perfect combustion therein for the purposes specified, a cooler, products of combustion connections from the hot stoves and auxiliary heat generator to the cooler, Cottrell apparatus, and products of combustion and fumes connections from the cooler thereto, substantially 10 as described.

3. Apparatus for the recovery of phosphoric acid or the like from raw materials comprising in combination a furnace having means for introduction of the raw materials and fuel and fluxing material, together with a suitable gas and fumes delivery connection and having suitable tuyères, of hot stoves in conjunction with said furnace, hot blast connections therefrom to the furnace tuyères, a connection for the delivery of gas and fumes from the furnace to the hot stoves for combustion therein of gas and fumes necessary to heat the air blast for the furnace, regulators at the hot stoves operable according to the differential of pressure between gas and fumes supply and air supply thereto for insuring substantially perfect combustion therein for the purposes specified, a cooler, products of combustion connections from the hot stoves to the cooler, Cottrell apparatus, and products of combustion and fumes connections from the cooler thereto, substantially as described.

4. Apparatus for the recovery of phosphoric acid or the like from raw materials comprising in combination a furnace having means for introduction of the raw materials and fuel and fluxing material, together with a suitable gas and fumes delivery connection and having suitable tuyères, of hot stoves in conjunction with said furnace, hot blast connections therefrom to the furnace tuyères, a connection for the delivery of gas and fumes from the furnace to the hot stoves for combustion therein of gas and fumes necessary to heat the air blast for the furnace, regulators at the hot stoves operable according to the differential of pressure between gas and fumes supply and air supply thereto for insuring substantially perfect combustion therein for the purposes specified, Cottrell apparatus, and products of combustion and fumes connections thereto, substantially as described.

5. Apparatus for the recovery of phosphoric acid or the like from raw materials comprising in combination a furnace having means for introduction of raw materials and fuel and fluxing material, together with a suitable gas and fumes delivery connection and having suitable tuyères, of regenerating apparatus in conjunction with said furnace, hot blast connections therefrom to the furnace tuyères, a connection for the delivery of gas and fumes from the furnace to the re-

generating apparatus for combustion thereof of gas and fumes necessary to heat the air blast for the furnace, regulators at the regenerating apparatus operable according to the differential of pressure between gas and fumes supply and air supply thereto, for insuring substantially perfect combustion therein for the purposes specified, suitable apparatus for recovering the phosphoric acid from the products of combustion from 75 the regenerating apparatus, and products of combustion and fumes connections thereto, substantially as described.

6. Apparatus for the recovery of phosphoric acid or the like from raw materials comprising in combination a furnace having means for introduction of the raw materials and fuel and fluxing material, together with the suitable gas and fumes delivery connection and having suitable tuyères for the introduction of air blast, of a closed combustion chamber, connections for introduction thereinto of gas and fumes delivered from the furnace and air for combustion, a regulator in conjunction with said connections 90 operable according to the differential of pressure between gas and fumes supply and air supply thereto for insuring substantially perfect combustion in said closed chamber for the purposes specified, Cottrell apparatus, and products of combustion and fumes connections thereto from said combustion chamber, substantially as described.

7. Apparatus for the recovery of phosphoric acid or the like from raw materials comprising in combination a furnace having means for introduction of the raw materials and fuel and fluxing materials, together with a suitable gas and fumes delivery connection and having suitable tuyères for the introduction of air blast, of a closed combustion chamber, connections for the introduction thereinto of gas and fumes delivered from the furnace and air for combustion, a regulator in conjunction with said connections operable according to the differential of pressure between gas and fumes supply and air supply thereto for insuring substantially perfect combustion in said closed chamber for the purposes specified, suitable apparatus for recovering desired end products, and products of combustion and fumes connections thereto from said combustion chamber, substantially as described.

8. Apparatus for the recovery of desired end products from raw materials including a furnace for the reduction of said raw materials together with production of producer gas and fumes therein, a closed combustion chamber, gas and fumes connections from the furnace to said combustion chamber, an air connection to said combustion chamber, a regulator in conjunction with the gas and fumes and air connections and combustion chamber operable according to the differen- 120
125
130

tial of pressure between gas and fumes supply and air supply thereto for insuring substantially perfect combustion therein for the purposes specified, Cottrell apparatus, and products of combustion and fumes connections from the combustion chamber thereto, substantially as described.

9. Apparatus for the recovery of desired end products from raw materials including 10 a furnace for the reduction of said raw materials together with production of producer gas and fumes therein, a closed combustion chamber, gas and fumes connections from the furnace to said combustion chamber, an 15 air connection to said combustion chamber, a regulator in conjunction with the gas and fumes and air connections and combustion chamber operable according to the differential of pressure between gas and fumes supply and air supply thereto for insuring substantially perfect combustion therein for the purposes specified, suitable apparatus for the recovery of the desired end products, and products of combustion and fumes connections from the combustion chamber thereto, substantially as described.

10. Apparatus for the recovery of phosphoric acid or the like from raw materials comprising in combination a furnace having 30 means for introduction of the raw materials and fuel and fluxing materials, together with a suitable gas and fumes delivery connection, and having suitable tuyères for the introduction of air blast, of a closed combustion 35 chamber, connections for the introduction thereinto of gas and fumes delivered from the furnace and air for combustion, a regulator in conjunction with the gas and fumes and air connections whereby the proportions 40 of combustible gas and fume and of air are accurately controlled by establishing a definite relation between the static pressures of the combustible gas and fume and of the air and corresponding definite proportions 45 between the areas of exit of the gas and fume and of the air for the purposes speci-

fied, suitable apparatus for recovering desired end products, and products of combustion and fumes connections thereto from said combustion chamber, substantially as 50 described.

11. Apparatus for the recovery of the desired end products from suitable raw materials including a furnace wherein said raw materials are reduced with production of 55 producer gas and fumes, a combustion chamber, connections from the furnace to the combustion chamber for delivery of producer gas and fumes from the furnace thereto, an air supply connection to the combustion 60 chamber, means for accurately controlling the proportions of combustible gas and fume and of air by establishing a definite relation between the static pressure of the combustible gas and fumes and of the air and corresponding 65 definite proportions between the areas of exit of the gas and fume and of the air for the purposes specified, and means for recovering desired end products from the products of combustion of said chamber, sub- 70 substantially as described.

12. Apparatus for the recovery of desired end products from suitable raw materials including a furnace wherein said raw materials are reduced with production of producer gas and fumes, connections from the furnace for the delivery of producer gas and fumes therefrom, a regulating burner in conjunction with said connections at a point of combustion, whereby the proportions of 80 combustible gas and fume and of air are accurately controlled by establishing a definite relationship between the static pressures of the combustible gas and fume and of the air and corresponding definite proportions between the areas of exit from the burner of the gas and fume and of the air for the purpose specified, and means for recovering desired end products from the products of combustion of said chamber, 85 substantially as described.

ARTHUR J. BOYNTON.
